UNITED STATES PATENT OFFICE.

JAMES A. SMITHAM, OF SAN JUAN, TEXAS, ASSIGNOR TO VALLEY IRON WORKS, OF SAN JUAN, TEXAS, A CORPORATION OF TEXAS.

HEAD GATE.

Application filed June 29, 1926. Serial No. 119,595.

My invention relates to head or water gates and particularly to the cover or valve; and the object is to provide a valve or cover which will prevent leakage and which will 5 be automatically locked when it is closed and in addition to the automatic lock, the head or gate is provided with a manually actuated lock which co-operates with the automatic lock. Another object is to make provision 10 for locking the gate at any elevation to which the gate may be raised. Another object is to provide the gate with both a vertical motion and a rocking motion. Another object is to simplify the construction and to make 15 a stronger frame. Other objects and advantages will be fully explained in the following description and the invention will be more particularly pointed out in the claims.

Reference is had to the accompanying 20 drawings which form a part of this application.

Fig. 1 is a front elevation. Fig. 2 is a side elevation of the gate or head with the jack not shown. Fig. 3 is a side elevation of the 25 head gate with the valve shown in section. Fig. 4 is a plan view of the valve with the front brace left off, that is, the front brace of the cross head is omitted. Fig. 5 is a horizontal section taken on the line 5—5 of 30 Fig. 1. Fig. 6 is a detail view of the threaded plunger.

Similar characters of reference are used to 35 indicate the same parts throughout the several views.

The improved gate or head is provided with upright frame members 1 and 2. A rack frame member 3 is bolted to the members 1 and 2 and serves as a part of the frame of the head gate. A bell or union 4 is to 40 be embedded in concrete or connected with a pipe. This bell has a flange 5 on each side bolted to the uprights 1 and 2. The frame members 1 and 2 are partly embedded in concrete. See Fig. 5. The frame members 1 and 2 will be rigid with the bell 4 whether this bell is embedded in concrete or 45 connected to a pipe. The gate 6 is pivotally mounted on a horizontal brace 7 or cross-head which is slidably mounted on the frame members 1 and 2, by means of flanged guides 8 which move vertically on the flanges of the uprights 1 and 2. The gate 6 has a shank or handle 9 to which is bolted a lever or handle 10. The gate can be elevated 50 manually by using the handle 10 when the

pressure of the water is not great, but when there is great pressure of the water it is necessary to use a jack. When the pressure is not great, the handle 10 need not be provided with the rack 11, but when the water 60 pressure is heavy, the rack 11 is necessary, and a jack is used to move the handle.

The gate 6 is carried by the cross-head or brace 7 and is connected to this brace by a worm or threaded plunger 12 which is 65 bolted to the brace 7 by bolts 13 and the connection is completed by two internally threaded nut members 14 which are bolted to two lugs 15 which are cast on the gate 6. The gate 6 has a cavity 16 which receives 70 the inner edges of the nut members 14. The worm 12 and the nut members 14 cause the gate 6 to move towards and from the mouth of the bell 4 when the gate is turned by the handle 10 by moving the handle to the right 75 and left respectively. The handle 10 is turned to the right or clockwise to close the bell liquid tight and may be locked in such position by a dog 17 which is slidably mounted on the handle 10 and is adapted to engage 80 the teeth of the rack frame 3.

The gate 6 can be elevated by the handle 10 and locked in the elevated position in the same manner, that is, by turning the handle to the right so that the gate will be pressed 85 against some part of the frame members 1 and 2.

The dog 17 is carried by a handle 18 and this handle may be locked to the lever or handle 10. This will keep the gate 6 locked 90 so that unauthorized persons cannot obtain water or other liquid.

At times when the flow of liquid is strong, a jack is necessary to lower the head gate, as the jack must force the gate down with 95 sufficient force to overcome the momentum of the liquid. The jack is adapted to force the gate downwardly but not upwardly.

When the liquid pressure is heavy, a jack 100 is necessary to lower the gate 6. A second frame member 3' is attached to the uprights 1 and 2 and the jack frame members 19 and 20 are mounted on the frame members 3 and 3'. See Figs. 1 and 3. The members 19 and 20 have flanges 21 which catch under flanges 105 on the frame members 3 and 3' and are braced thereon by bolts 22. A pinion 23 is journaled in the bearing members 20 and 19 and a crank 24 is provided for the pinion 23. Guide members 25 project on both sides of 110

the handle 10 and hold the pinion 23 in line to mesh with the rack 11.

The flanges 21 are caught under the frame members 3 and 3' and the pinion 23 is placed in mesh with the rack 11 and held in mesh by any suitable means, as a pin carried by a chain. The crank 24 is then turned to cause the pinion 23 to move the rack 11 vertically, and as the jack cannot go upwardly, the pinion 23 will drive the rack 11 downwardly to force the head 6 downwardly to stop the flow of water.

What I claim, is,—

1. A head gate comprising a frame and a bell or union attached thereto, a cross-head slidably engaging said frame and a gate carrying said cross-head, means for tightening said gate against said bell consisting of a threaded plunger attached to said cross-head and a threaded clamp attached to said gate and engaging said plunger, a handle at-

tached to said gate, a rack attached to said frame, a dog carried by said handle adapted to engage said rack, and means for locking said dog to said rack at different positions of said gate. 25

2. A head gate comprising a frame having upright members and a bell attached to said upright members, a gate provided with a cross-head having guide flanges having sliding engagement with said uprights, a handle for moving said gate vertically and turning said gate, means for locking said gate in any position to which it may be turned, and means for operatively connecting said cross-head and said gate consisting of a threaded nut member attached to said gate and a threaded plunger attached to said cross-head. 30

In testimony whereof, I set my hand, this 10th day of August, 1925.

JAMES A. SMITHAM.
